Primary Examiner — Eric L Goodman*Assistant Examiner* — Sanjeev Paul(74) *Attorney, Agent, or Firm* — Symbus Law Group, LLC; Clifford D. Hyra(57) **CLAIM**

The ornamental design for a set of seat cushions, as shown and described.

DESCRIPTION

FIG. 1 is a perspective view of the set of seat cushions, showing the rear and top sides thereof;

FIG. 2 is a top view thereof;

FIG. 3 is a bottom view thereof;

FIG. 4 is a rear view thereof;

FIG. 5 is a front view thereof;

FIG. 6 is a left side view thereof; and,

FIG. 7 is a right side view thereof.

The broken lines in the drawings are included for the purpose of illustrating subject matter that forms no part of the claimed design.

1 Claim, 7 Drawing Sheets# US D828,701 S
